(57) **CLAIM**

The ornamental design for a wireless headphone, as shown and described.

DESCRIPTION

FIG. 1 is a right side perspective view of the wireless headphone in accordance with the present invention;

FIG. 2 is a left side perspective view of the wireless headphone shown in FIG. 1;

FIG. 3 is a left side elevational view of the wireless headphone shown in FIG. 1;

FIG. 4 is a front view of the wireless headphone shown in FIG. 1;

FIG. 5 is a right side elevational view of the wireless headphone shown in FIG. 1;

FIG. 6 is a rear view of the wireless headphone shown in FIG. 1;

FIG. 7 is a top view of the wireless headphone shown in FIG. 1; and,

FIG. 8 is a bottom view of the wireless headphone shown in FIG. 1.

The broken lines shown in FIGS. 1, 2, 4, 6, 7, and 8 are for the purpose of illustrating environmental structure and form no part of the claimed design.
